UNITED STATES PATENT OFFICE.

FREDERICH GEORGE NIEMEYER, OF DENISON, TEXAS.

FACING-BLOCKS.

1,140,913.

Specification of Letters Patent. Patented May 25, 1915.

Application filed September 29, 1914. Serial No. 864,038.

To all whom it may concern:

Be it known that I, FREDERICH G. NIEMEYER, a citizen of the United States, and residing at Denison, in the county of Grayson and State of Texas, have made certain new and useful Improvements in Facing-Blocks.

This invention relates to building structures, and more particularly to an improved veneer or facing for use with wooden or metal frame-work.

One of the principal objects of the invention is to provide an improved facing block having means for facilitating the ready connection of the block with the frame-work of a building.

Another object of the invention is to provide a frame-work facing made up of a plurality of blocks having uncemented tongue and groove connections with each other, and having each a single point of suspension from the frame-work, whereby relative movement and adjustment may be had between the blocks, upon vibration or settlement of the frame-work.

A further object contemplates the provision of a facing block which will be extremely simple, durable, efficient in operation and inexpensive to manufacture.

With these and other objects in view, which will become apparent as the description proceeds, the invention resides in the construction, combination and arrangement of parts hereinafter more fully described, and illustrated in the accompanying drawing in which like characters of reference indicate like parts throughout the figures, of which;

Figure 1 represents a horizontal sectional view taken through one corner of a building incorporating my invention in its construction, Fig. 2 represents a detail vertical transverse sectional view taken on the plane indicated by the line 2-2 of Fig. 1 and looking in the direction indicated by the arrows, Fig. 3 represents a front elevational view of one of the facing blocks, Fig. 4 represents a view similar to Fig. 3, typifying the blocks used at the corners of a building.

The frame-work to which the blocks are connected, may be constructed of wood or metal, and includes the vertical studs 5 and horizontal laths or strips 6 connecting said studs in parallel and spaced relation with each other. The facing blocks may be

formed of any suitable and desirable material, and are substantially rectangular in shape, one longitudinal edge and one lateral edge, 7 and 8 respectively, of each block, 60 being provided with a tongue, while the respectively opposite longitudinal and lateral edges 9 and 10 are provided with a groove. In assembling the block to form the facing, the longitudinal edge 7 is uppermost and the 65 edge 8 occurs at the right hand end of the block, while edges 9 and 10 respectively form the bottom and left hand edges of each block.

Each block is provided near its upper edge 70 with a reinforcement 11 embedded therein, said reinforcement, preferably taking the form of a single or a plurality of strands of barbed wire. A tie wire 12 is provided for each block, by means of which said block 75 may be suspended from the frame-work. At one end said tie wire is secured to the reinforcement 11 and is embedded in the block, the opposite end of the tie wire emerging from the block at the rear face and near the 80 upper edge thereof.

In assembling the blocks, the tie wires are passed under and around the laths or strips 6 and are twisted upon or suitably secured to nails or other anchoring means 13 85 provided in the top edges of the laths in the manner clearly indicated in Fig. 2. The laths are arranged so that their centers are spaced apart a distance substantially equal to the width of the blocks, so that when said 90 blocks are in position the upper and lower edges of each of them rests against adjacent laths.

The blocks are arranged so that the tongues of each block engage in the grooves 95 of the adjacent upper and lateral blocks, and the joints thus provided are not cemented as is the usual case, but are left free of any cement or mortar or similar substance, whereby any vibrations or settling of the 100 frame-work will be compensated for by slight shifting or readjustment of the blocks, so that the latter will not be broken or cracked; a disadvantage accruing to many forms of facing blocks. Since each block 105 has but a single point of suspension from the frame-work, it will be readily understood that a slight movement or oscillation of the blocks to accommodate the vibration of the frame-work, will be allowed.

The corner blocks indicated at 14, may be of a different design from the other blocks,

if so desired, the outer ends of those nearest the corner being thickened at 15 in the type of corner block shown in Fig. 4, although it will be understood this variation in design is merely for the purpose of presenting an attractive exterior, and does not modify the mode of operation of the blocks. However, the corner blocks have their outer edges mitered at 16, as indicated in Fig. 1, 10 so as to make a perfect fit at the corners of the frame, and a cement filler 17 may if desired be placed in the channel or groove occurring between the corner blocks of adjacent sides. The corner blocks are also 15 suspended by means of tie wires in the manner already indicated. The outer faces of the blocks may be plain or designed to imitate stone, and may be molded or milled to present any desired finish. The edges 20 bounding the outer face of each block are rounded as indicated.

Although I have described the preferred embodiment of my invention, I may desire to make such changes in the construction, 25 combination and arrangement of parts thereof, as do not depart from the spirit of

the invention and the scope of the appended claims.

I claim:—

1. A building including a plurality of 30 horizontally spaced strips, a plurality of facing blocks each provided with means for securing the same at a single point to one of the horizontal strips, said blocks having interlocked tongue and groove connections, 35 said connections being uncemented.

2. A building including a framework, a plurality of blocks, a flexible tie for suspending each block at a single point from the framework, said blocks having interlocked uncemented connections, whereby the blocks may readjust themselves to accommodate vibration or settling of the frame. 40

3. The combination of a frame and a plurality of blocks suspended each from the 45 frame at a single point and having interlocking uncemented connections.

FREDERICK GEORGE NIEMEYER.
